UNITED STATES PATENT OFFICE.

ROBERT W. SCOTT, OF LEEDS POINT, NEW JERSEY, ASSIGNOR OF ONE-HALF TO LOUIS N. D. WILLIAMS, OF OGONTZ, PENNSYLVANIA.

KNITTED FABRIC AND MODE OF MAKING SAME.

No. 830,373.

Specification of Letters Patent.

Patented Sept. 4, 1906.

Application filed September 20, 1905. Serial No. 278,304.

To all whom it may concern:

Be it known that I, ROBERT W. SCOTT, a citizen of the United States, residing at Leeds Point, New Jersey, have invented certain Improvements in Knitted Fabrics and Modes of Making the Same, of which the following is a specification.

My invention relates to that class of knitted fabrics which are partly ribbed and partly plain, the object of my invention being to produce a machine-knit fabric of this character, especially one of fine gage, in which the change from rib-stitch to plain stitch or the reverse can be readily effected by manipulation of the needles and without stopping the machine or requiring the intervention of an attendant, the invention being therefore especially adapted for use in the manufacture of hosiery upon automatic knitting-machines.

In the accompanying drawings, Figures 1, 2, and 3 are views, on an exaggerated scale, of pieces of knitted fabric, illustrating the manner in which change from rib-knitting to plain knitting may be effected in accordance with my invention. Fig. 4 is a plan view illustrating the relation to each other of the needles of the machine and the stitches of the knitted web during the production of ribbed fabric. Fig. 5 is a similar view illustrating the relation of the needles and stitches at the beginning of the transferring operation in accordance with my invention. Fig. 6 is a sectional view illustrating the relation of the needles during the operation of knitting ribbed web. Figs. 7 and 8 are similar views illustrating the movements of the needles in effecting the transfer of a stitch from one needle to another. Fig. 9 is an inverted plan view of the needle-dial jacks and of the cams for acting upon the same. Figs. 10, 11, and 12 are views similar to Figs. 1, 2, and 3, but illustrating a fabric in which a change from plain web to ribbed web has been effected; and Fig. 13 is a view of a cylinder-needle such as may be used in knitting the latter fabric.

In Figs. 1, 2, and 3 of the drawings, *m* represents the wales of one face of the ribbed fabric, and *n* represents the wales of the other face of the same, the wales *m'* and *n'* being those of the plain-knitted fabric, *m'* being a continuation of the standing wales *m*, which appear in both the plain and ribbed web, and *n'* being a continuation of and substitute for the rib-wales *n*.

In the fabric shown in Fig. 1 some of the stitches of the first course *a* of plain web engage with stitches of the last course *b* of ribbed web, and other stitches of said first course *a* of the plain web engage with ribbed stitches of the course *c* preceding the last. In the fabric shown in Fig. 2 some of the stitches of the first course *a* of plain web engage with stitches of the last course *b* of ribbed web and with stitches of the last course *b* of such ribbed web and with stitches of the course *c* preceding the same. In the fabric shown in Fig. 3 the stitches of the first course *a* of plain web all engage with stitches of the last course *b* of ribbed web.

In carrying out my invention I use a machine having cylinder and dial, the cylinder being provided with standing wale-needles *x*, which are operative both in producing ribbed web and in producing plain web, these needles alternating with needles *w*, which are not in operation when ribbed web is being knitted, but which receive stitches from the dial-needles *y* in changing from ribbed web to plain web. Such machine forms the subject of my application for patent, Serial No. 288,911, filed November 24, 1905.

Various means may be adopted for so operating the dial-needles that they can be caused to transfer their stitches to the rib-supplanting cylinder-needles at the proper time, my present invention being independent of the specific means employed for this purpose. In Figs. 6 to 8, however, I have illustrated devices which are available for the purpose and which will be sufficient to suggest to those skilled in the art other means for accomplishing the desired result. In connection with the cylinder 15 and dial 16 of the machine I employ dial-needles *y*, carried by swinging jacks 19, so that they may work in the grooves of the dial or may be carried out beyond their normal or knitting position, depending upon whether they are operated by the normal cams 20 20^a of the cam-plate 21 or by special cams 22 22^a of the same. When the dial-needles *y* are abnormally projected, their butts or stems will draw stitches of the ribbed web over the retracted rib-supplanting cylinder-needles *w*, and the latter can then be projected so as to enter and engage said stitches.

Fig. 6 shows the standing wale-needles *x* of the cylinder and the dial-needles *y* in the operative positions assumed by them during

rib-knitting, the rib-supplanting needles *w* being retracted, and Fig. 7 shows a dial-needle *y* projected so that its butt or stem draws out the rib-stitch carried thereby and pulls the rib-stitch preceding the same into such a position above the cylinder that when the cylinder-needle *w* is projected, as shown in said figure, it will enter and engage said preceding stitch. If now the cylinder-needle *w* is retracted again, as shown in Fig. 8, it will draw down the stitch which it has engaged and will permit the dial-needle *y* to be retracted over its hooked end, so that said dial-needle can cast the stitch which it carried. 10 If the stitch thus cast by the dial-needle can slip over the top of the needle *w*, the result when the knitting of plain web upon all of the cylinder-needles is proceeded with will be that shown in Fig. 1, the stitches which were 15 cast from the dial-needles pulling into the adjoining standing wales and the yarn being drawn across the engaged stitches. If, however, the stitches cast from the dial-needles are caught by the cylinder-needles *w*, either 20 when they are cast off or when the needles *w* subsequently rise, as at the knitting-point, both stitches will be delivered by the needles *w* when the first course of plain web is knitted, the resulting fabric being as shown in 25 Fig. 2.

The fabric shown in Fig. 3 is produced by projecting each cylinder-needle *w* so that it will engage the stitch carried by the dial-needle and then retracting the latter while the 30 needle *w* is still projected, whereby the dial-needle will cast its stitch onto said needle *w*. This will involve the crowding or shogging of the dial-needle into a plane alongside of that occupied by the needle *w* and also the crowding 35 of the two needles into the same stitch, and hence I do not regard this method of transfer with the same favor as either of the other methods described.

In any method of transferring stitches 40 from a dial-needle to a cylinder-needle, or vice versa, by direct action of the needles themselves it is important that there shall be no partially-projected needle or needles in advance of the first fully-projected transfer-needle, because of the liability of the partially-projected needles to be withdrawn without having transferred their stitches, which 45 stitches will consequently be cast or dropped. For this reason machines having cams which 50 travel in a direction transverse to the direction of movement of the needles and also in changing from inoperative to operative position swing or travel in a direction parallel with such movement of the needles cannot, especially in fine-gage machines, effect a proper 55 transfer of stitches, since one or more of the needles must necessarily pass from under the control of the cam during the time that the latter is moving from its retracted to its projected position, or vice versa, and these par-

tially-projected needles will be retracted by the following draw-in cam, so as to cast their stitches. It is also important that the needles from which the stitches are to be transferred should after having been projected to 70 the transfer position and then retracted be held out of range of the knitting-cams in order to prevent any of them from being again projected so as to receive yarn, as any loops of knitting-yarn thus applied thereto would 75 prevent the proper formation of the stitches of plain web upon the other set of needles. In carrying out my invention, therefore, the first fully-projected dial transfer-needle, as shown in Fig. 5, adjoins a fully-retracted 80 dial-needle, the latter being the last to be acted upon. Hence the transfer always begins at a certain needle of the set and ends at the adjoining needle after the stitches have been transferred from the intervening needles, 85 and each rib-wale must therefore necessarily be transferred to a corresponding plain wale. Each dial-needle after being projected to the transfer-point is then withdrawn to an idle 90 position free from the influence of the knitting-cams. In like manner a certain needle of the cylinder corresponding to the first projected dial-needle should be the first to be projected to the stitch-receiving point, so that the transfer always begins on a certain 95 needle and ends on the adjoining needle. This can readily be accomplished by providing some of the jacks of the needles *y* with longer ends than the others and some of the needles *w* of the cylinder with special high 100 butts, which are acted upon by a cam whose movement into or out of action is not imparted to the needles.

In Fig. 9 I have shown both the knitting-cams 20 20^a and the transfer-cams 22 22^a in 105 operative relation with the ends of the jacks, 20 representing the knitting-cam which projects the dial-needles and 20^a the knitting-cam which retracts the same, while 22 represents the projecting transfer-cam and 22^a 110 the retracting transfer-cam. When the cams 22 and 22^a are passing the short or unshaded jacks, they are partially depressed or moved in line longitudinally with the jacks, so as to act upon the long or shaded jacks; but as 115 soon as they have passed to their full extent behind said long jacks they can be further depressed, so as to act upon the short jacks. It will be noted that the cam 22^a delivers the 120 jacks outside of the range of the knitting-cams, so that when the dial-needles are withdrawn from action after transferring their stitches they will remain out of action until the cam 22^a is again retracted, whereupon 125 the jacks will be moved by a cam 23 so as to again come under the influence of the knitting-cams. The projecting transfer-cam 22 is moved out of action as soon as may be after the transferring of the stitches from the 130 full series of dial-needles has been effected.

A knitted web produced in accordance with my invention has as many wales of stitches in the plain portion as in the ribbed portion, and the change from rib-knitting to plain knitting is effected without formation of eyelet-holes or other gaps in the knitted web.

The fabric is, by preference, knitted with a single continuous yarn composed either of one strand or a plurality of strands, or it may have additional strands added to it in knitting certain portions of the web, the term "continuous" not necessarily implying unbroken continuity, as yarns of different color may be used in different portions of the web so long as the meeting ends of said yarns overlap or provide for a continuous feed of yarn to the needles of one and the same machine. This serves to distinguish a fabric made in accordance with my invention from one which is produced by knitting the ribbed web upon one machine and then transferring the stitches of said ribbed web to another machine for knitting the plain web, as such ribbed web in that case must necessarily be knitted with yarn disconnected from that employed in knitting the plain web.

My invention in its broader embodiment is applicable to the manufacture of fabric in which the change is effected from plain knitting to rib-knitting, stitches of plain web in this case being transferred from the cylinder-needles *w* to the dial-needles *y* instead of the reverse operation, as before described, the cylinder-needles *w* having special butts or projections *w'* to engage and pull up the stitches upon the needles and permit the dial-needles to enter the same or preceding stitches of the web. (See Fig. 13.) In Figs. 10 to 12 I have shown the various forms of fabric which may be produced when this mode of operation is resorted to, *a'* in these views representing the last course of plain web, *b'* the first course of ribbed web, and *c'* the course of plain web which precedes the last.

Prior to my invention machines have been devised for the purpose of changing from rib-knitting to plain knitting by transferring stitches from dial-needles of the machine to cylinder-needles of the same; but such machines, so far as I am aware, have always required some special means for spreading the transferred loops and have therefore been impracticable for use in the production of "fine-gage" web, meaning by this web having more than eight or nine wales to the inch, or the machines have not been such that the transfer could be begun at one needle of the dial and finished at the adjacent needle, the result being that certain needles would cast their stitches before the latter could be transferred, and the machine would not, therefore, effect the transfer of all of the rib-strokes to corresponding plain-stitch wales, or the re-

verse. By transferring to the newly-introduced needles *w* stitches of a previously-formed course of the ribbed web instead of stitches of the last course which still remain upon the needles which produced them I 70 overcome the objection which attends an attempt to transfer a stitch directly from one needle to another, as I am not obliged to force two needles or other implements through one stitch, which in a normal fabric 75 is only sufficiently large to surround the needle upon which it is formed, and I also avoid the use of transfer-points or other instrumentalities than the needles themselves in effecting the transfer of the stitches. 80

My invention is not limited to that class of fabrics in which each cylinder-needle wale alternates with a dial-needle wale, as in the fabric shown, and which is known as a "one-and-one" ribbed fabric, my invention being 85 equally applicable to other combinations of wales—such, for instance, as a two-and-two rib, five-and-one rib, or any other of the well-known ribbed fabrics. It will also be understood that although I have described 90 my invention as applicable to the production of circular webs it can be employed in the production of flat webs also.

Having thus described my invention, I claim and desire to secure by Letters Patent—

1. A knitted fabric comprising both ribbed and plain webs, some of the stitches of the first course of one web meshing with stitches of the last course of the other web and others 100 with stitches of a course preceding the same.

2. A knitted fabric comprising both ribbed and plain webs, some of the stitches of the first course of one web meshing with the last course of stitches of the other web, and alternate stitches of the first course of the first web meshing with stitches of a course of the other web preceding the last course. 105

3. A knitted fabric comprising both ribbed and plain webs, some of the stitches of the first course of one web meshing with stitches in the last course of the other web, and others with stitches of said last course and of a course preceding the same. 110

4. A knitted fabric comprising both ribbed and plain webs, certain stitches of the first course of one web meshing with stitches of the last course of the other web, and alternate stitches of said first course of the first web meshing with stitches of said last course 120 and of a course preceding the same. 115

5. A seamless tubular-knitted fabric comprising both ribbed and plain webs, some of the stitches of the first course of one web meshing with stitches of the last course of 125 the other web and others with stitches of a course preceding the same.

6. A seamless tubular-knitted fabric comprising both ribbed and plain webs, some of the stitches of the first course of one web 130

- meshing with the stitches of the last course of the other web, and alternate stitches of the first course of the first web meshing with stitches of a course of the other web preceding the last course.
5. A seamless tubular-knitted fabric comprising both ribbed and plain webs, some of the stitches of the first course of one web meshing with stitches in the last course of the other web, and others with stitches in said last course and in a course preceding the same.
7. A seamless tubular-knitted fabric comprising both ribbed and plain webs, some of the stitches of the first course of one web meshing with stitches in the last course of the other web, and others with stitches in said last course and in a course preceding the same.
8. A seamless tubular-knitted fabric comprising both ribbed and plain webs, certain 15 stitches of the first course of one web meshing with stitches of the last course of the other web, and alternate stitches of said first course of the first web meshing with stitches in said last course and in a course preceding the same.
9. A knitted fabric comprising both ribbed and plain webs, some of the stitches of the first course of the plain web meshing with stitches of the last course of the ribbed web 25 and others with stitches of a course preceding the same.
10. A knitted fabric comprising both ribbed and plain webs, some of the stitches of the first course of the plain web meshing with 30 the last course of stitches of the ribbed web, and alternate stitches of the first course of the plain web meshing with stitches of a course of the ribbed web preceding the last course.
11. A knitted fabric comprising both ribbed and plain webs, some of the stitches of the first course of the plain web meshing with stitches of the last course in wales of one 35 face of the ribbed web, and other stitches of said first course of the plain web meshing with stitches of a preceding course in wales of the other face of said ribbed web.
12. A knitted fabric comprising both ribbed and plain webs, some of the stitches of the first course of the plain web meshing with 45 stitches in the last course of the ribbed web, and others with stitches of said last course and of a course preceding the same.
13. A knitted fabric comprising both ribbed and plain webs, certain stitches of the first course of the plain web meshing with 50 stitches of the last course of the ribbed web, and alternate stitches of said first course of the plain web meshing with stitches of said last course and of a course preceding the same.
14. A knitted fabric comprising both ribbed and plain webs, some of the stitches of the first course of the plain web meshing with 55 stitches of the last course in wales of one face of the ribbed web, and other stitches of said first course of the plain web meshing with stitches of said last course and of a preceding course in wales of the other face of the 60 ribbed web.
15. A seamless tubular-knitted fabric comprising both ribbed and plain webs, some of the stitches of the first course of the plain web meshing with stitches of the last course of the ribbed web and others with stitches of a course preceding the same.
16. A seamless tubular-knitted fabric comprising both ribbed and plain webs, some of the stitches of the first course of the plain web meshing with stitches of the last course of the ribbed web, and alternate stitches of the first course of the plain web meshing with 70 stitches of a course of the ribbed web preceding the last course.
17. A seamless tubular-knitted fabric comprising both ribbed and plain webs, some of the stitches of the first course of the plain web meshing with stitches of the last course in wales of one face of the ribbed web, and other 75 stitches of said first course of the plain web meshing with stitches of a preceding course in wales of the other face of said ribbed web.
18. A seamless tubular-knitted fabric comprising both ribbed and plain webs, some of the stitches of the first course of the plain web meshing with stitches in the last course of the ribbed web, and others with stitches in said last course and in a course preceding the same.
19. A seamless tubular-knitted fabric comprising both ribbed and plain webs, certain 85 stitches of the first course of the plain web meshing with stitches of the last course of the ribbed web, and alternate stitches of said first course of the plain web meshing with stitches in said last course and in a course preceding the same.
20. A seamless tubular-knitted fabric comprising both ribbed and plain webs, some of the stitches of the first course of the plain web meshing with 90 stitches of the last course in wales of one face of the ribbed web, and other stitches of said first course of the plain web meshing with stitches in said last course and also in a preceding course in wales of the other face of the ribbed web.
21. The mode herein described of effecting a change of web in a machine-knit fabric, having standing wales common to both webs said mode consisting in drawing out stitches of certain wales so that needles introduced between the standing wales can enter stitches preceding those thus drawn out, engaging 105 said preceding stitches by said newly-introduced needles, casting the drawn-out stitches from their needles, and then knitting further 110 web upon the standing wale-needles and the newly-introduced needles.
22. The mode herein described of effecting a change of web in a machine-knit fabric, having standing wales common to both webs said mode consisting in drawing out stitches of certain wales so that needles introduced 115 between the standing wales can enter stitches preceding those thus drawn out, engaging 120 said preceding stitches by said newly-introduced needles, casting the drawn-out stitches from their needles, and then knitting further 125 web upon the standing wale-needles and the 130 newly-introduced needles.

duced needles, casting the drawn-out stitches from their needles and onto the newly-introduced needles, and then knitting further web upon the standing wale-needles and the 5 newly-introduced needles.

23. The mode herein described of effecting a change from ribbed knitting to plain knitting in a machine-knit fabric, having standing wales common to both webs said mode 10 consisting in drawing out stitches of the rib-wales so that needles introduced between the standing wales can enter rib-strokes preceding those last formed, engaging said preceding stitches by said newly-introduced needles, 15 casting the last-formed rib-strokes from their needles, and then knitting plain web upon the standing wale-needles and the newly-introduced needles.

24. The mode herein described of effecting a change from ribbed knitting to plain knitting in a machine-knit fabric, having standing wales common to both webs said mode 20 consisting in drawing out stitches of the rib-wales so that needles introduced between the standing wales can enter rib-strokes preceding those last formed, engaging said preceding stitches by said newly-introduced needles, 25 casting the last-formed rib-strokes from their needles and onto the newly-introduced needles, 30 and then knitting plain web upon the standing wale-needles and the newly-introduced needles.

25. The mode herein described of effecting a change of web in a machine-knit fabric, 35 said mode consisting in knitting upon a set of needles and at the same time, but at another point, transferring stitches from said needles to another set of needles by projecting the first transferring-needles until a stitch of the 40 web produced thereby is drawn into the path of the receiving-needle, but without clearing the stitch on a needle in advance of said first transferring-needle, continuing such projection of transferring-needles in proper order, 45 advancing in like manner the receiving-needles to engage the stitches to be transferred, and then casting the stitches from the transferring-needles onto the receiving-needles.

26. The mode herein described of effecting a change of web in a machine-knit fabric, 50 such mode consisting in first knitting upon two sets of needles to produce a ribbed fabric, and at the same time, but at another point, transferring stitches from some of the needles 55 to others by projecting the first transferring-needle until a stitch of the web produced thereby is drawn into the path of the receiving-needle but without clearing the stitch on a needle in advance of said first transferring-needle, 60 continuing such projection of transferring-needles in proper order, advancing in like manner the receiving-needles to engage the stitches to be transferred, and then casting the stitches from the transferring- 65 needles onto the receiving-needles.

27. The mode herein described of effecting a change of web in a machine-knit fabric, 70 said mode consisting in knitting upon two sets of needles to produce a ribbed web, and at the same time, but at another point, transferring stitches from needles of one set to needles of the other set by projecting the first transferring-needle until a stitch of the web produced thereby is drawn into the path of the receiving-needle but without clearing the 75 stitch on a needle in advance of said first transferring-needle, continuing such projection of transferring-needles in proper order, advancing in like manner the receiving-needles to engage the stitches to be transferred, and 80 then casting the stitches from the transferring-needles onto the receiving-needles.

28. The mode herein described of effecting a change of web in a machine-knit fabric, 85 said mode consisting in knitting upon one set of needles and upon certain needles of another set to produce a ribbed fabric, and at the same time, but at another point, transferring stitches from needles of the first set to previously-inactive needles of the second set 90 by projecting the first transferring-needle until a stitch of the web produced thereby is drawn into the path of the receiving-needle but without clearing the stitch on a needle in advance of said first transferring-needle, 95 continuing such projection of transferring-needles in proper order, advancing in like manner the receiving-needles to engage the stitches to be transferred, and then casting the stitches from the transferring-needles 100 onto the receiving-needles.

29. The mode herein described of effecting a change of web in a machine-knit fabric, 105 said mode consisting in fully projecting a needle of one set without projecting a neighboring needle on one side of it and continuing such projection of needles outwardly from the first needle until the full set has been projected, at the same time and in like manner projecting needles of another set so that they 110 will, in proper order, enter stitches of the web carried by the needles of the first set, which 115 stitches have been formed in advance of those upon the projected needles of said first set, then withdrawing the latter needles so as to 120 cast the stitches from them, and then knitting further web upon the standing wale-needles and the newly-introduced needles.

30. The mode herein described of effecting a change of web in a machine-knit fabric, 125 said mode consisting in fully projecting a needle of one set without projecting a neighboring needle on one side of it and continuing such projection of needles outwardly from the first needle until the full set has been projected, at the same time and in like manner projecting needles of another set so that they 130 will, in proper order, enter stitches of the web carried by the needles of the first set, which stitches have been formed in advance of

those upon the projected needles of said first set, then withdrawing the latter needles so as to cast the stitches from them and onto the newly-introduced needles, and then knitting further web upon the standing wale-needles and the newly-introduced needles.

31. The mode herein described of effecting a change from rib-knitting to plain knitting in a machine-knit fabric, said mode consisting in fully projecting a rib-stitch needle without projecting the neighboring rib-stitch needle on one side of it, and continuing such projection of rib-stitch needles onwardly from the first until the full set has been projected, at the same time and in like manner projecting needles of the other set, so that they will, in proper order, enter rib-strokes which have been formed in advance of those upon the projected rib-stitch needles, then withdrawing said rib-stitch needles so as to cast the stitches from them, and then knitting plain web upon the standing wale-needles and the newly-introduced needles.

32. The mode herein described of effecting

a change from rib-knitting to plain knitting in a machine-knit fabric, said mode consisting in fully projecting rib-stitch needles without projecting the neighboring rib-stitch needle on one side of it, and continuing such projection of rib-stitch needles onwardly from the first until the full set has been projected, at the same time and in like manner projecting needles of the other set, so that they will, in proper order, enter rib-strokes which have been formed in advance of those upon the projected rib-stitch needles, then withdrawing said rib-stitch needles so as to cast the stitches from them and onto the newly-introduced needles, and then knitting plain web upon the standing wale-needles and the newly-introduced needles.

In testimony whereof I have signed my name to this specification in the presence of two subscribing witnesses.

ROBERT W. SCOTT.
